(57) **CLAIM**

The ornamental design for a razor, as shown and described.

DESCRIPTION

FIG. 1 is a front top side perspective view of a razor with the cap;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded perspective view thereof;

FIG. 9 is a top side perspective view of the handle of the razor without the cap;

FIG. 10 is a magnified partial view thereof;

FIG. 11 is a front top side perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a front cross-sectional view thereof;

FIG. 19 is a side cross-sectional view thereof;

FIG. 20 is a magnified view of a front cross-sectional view thereof; and,

FIG. 21 is a magnified view of a side cross-sectional view thereof.

In the drawings, the broken lines are for the purpose of illustrating environment only, and form no part of the claimed design.
